UNITED STATES PATENT OFFICE.

CHARLES SCHIFFL, OF MONTCLAIR, NEW JERSEY, ASSIGNEE TO THOMAS A. EDISON,
INCORPORATED, OF WEST ORANGE, NEW JERSEY, A CORPORATION OF NEW JERSEY.

STOP MECHANISM FOR PHONOGRAFES OR TALKING-MACHINES.

1,294,955.

Specification of Letters Patent. Patented Feb. 18, 1919.

Application filed May 2, 1911. Serial No. 824,558.

To all whom it may concern:

Be it known that I, CHARLES SCHIFFL, a citizen of the United States, and a resident of Montclair, in the county of Essex and State of New Jersey, have made certain new and useful Improvements in Stop Mechanisms for Phonographs or Talking-Machines, of which the following is a description.

10 My invention relates to phonographs or talking machines, and more particularly to devices whereby such machines may be automatically stopped at the desired time during the travel of the reproducer or recorder.

The principal object of my invention is to provide a simple and inexpensive device for the purpose mentioned, which is sensitive but certain in its operation, and which 20 can be readily applied to ordinary phonographs or talking machines without special preparation or provision being made therefor. A further object of my invention is to provide a device of this character which can be readily adjusted to automatically stop the machine at the desired time. In my preferred construction, I attain these objects by the provision of stationary brake mechanism and an adjustable releasing member normally 25 movable with the reproducer or recorder and adapted to operate the brake mechanism to cause the latter to stop the rotation of the record support. As it is frequently desirable to stop the machine at times other than that for which the releasing member 30 is set, my invention also contemplates the provision of means for manually operating the brake mechanism. Means are also preferably provided for rendering the adjustable releasing member inoperative when it 35 is desired to dispense with the use of the same. Other objects of my invention will appear more fully in the following specification and appended claims.

40 In order that my invention may be more fully understood, attention is hereby directed to the accompanying drawing forming part of this specification and in which—

Figure 1 is a top plan view of a phono-

graph or talking machine equipped with my invention;

Fig. 2 is a fragmentary top plan view of my improved stopping mechanism, the adjustable releasing member being shown in contracted or operative position, and the sound conveying arm being shown in section taken on the line 2—2 of Fig. 4;

Fig. 3 represents a view similar to that shown in Fig. 2 but showing the adjustable releasing member in expanded or inoperative position;

Fig. 4 represents a vertical section taken on the line 4—4 of Fig. 3; and

Fig. 5 represents a fragmentary elevation of my preferred means for expanding the adjustable releasing member, this view being taken from the inside of said member

In all of the views, like parts are designated by the same reference numerals.

The phonograph or talking machine shown is of well known construction and comprises a rotatable turntable 1 adapted to support a record 2, the turntable being mounted on a vertical shaft 3 adapted to be rotated by a motor (not shown) in the casting 4. A sound conveying reproducer arm 5 is pivotally connected, as at 6, to a bracket 7 and carries at its forward end, a reproducer 8 which is connected thereto by a universal joint 9. The arm 5 extends downwardly into the cabinet 4 where it is connected with a sound amplifier 10 by which the sound vibrations from the diaphragm of the reproducer are amplified and given forth into the atmosphere through an opening or openings (not shown) in the front of the cabinet. In the construction shown, the reproducer and sound conveying arm 5 move across the record surface, the amplifying horn 10 being stationary, but my invention is not limited to this construction.

My improved stopping device comprises a brake mechanism 11, and a releasing member 12 adapted to automatically actuate the brake mechanism and stop the rotation of the turntable or record support 1 when the reproducer has reached the desired position on the record 2. The brake mechanism

comprises a brake member 13 pivoted, as at 13', to the top of the cabinet and provided near its outer end with a friction piece 14 which is adapted to be forced by the spring 15 into firm frictional engagement with the downturned flange 1' on the turntable or record support 1, and also comprises a pivoted latch or detent 16 adapted to hold the member 13 out of engagement with the flange 1', and an arm 17 adapted to manually set or release the latch or detent 16. The friction piece 14, which may be made of leather, felt, or any other suitable material, is secured to the forwardly extending arm 18 of the member 13 by the ears 19 which surround and firmly grip the said friction piece between them. The spring 15 is secured at its ends to the pins 20 and 21 which are secured to the top of the cabinet and to the member 13 respectively. This spring is located to the right of the pivot 13' so as to exert a constant tendency to force the member 13 into engagement with the flange 1'. The detent or latch 16 is mounted on a pivot screw 22 secured to the top of the cabinet and is provided on its left hand edge with an upwardly directed flange or projection 23 adapted to engage a notch 24 in the outer end of the member 13 to hold the said member out of operative position, as shown in solid lines in Fig. 2. The forward end of the detent or latch 16 is provided with an upwardly directed flange or projection 25 adapted to be engaged by the finger 26 on the releasing member 12; so that movement of said releasing member in a clockwise direction will move the detent 16 out of engagement with the member 13 to release the latter and thereby cause the same to be thrown by the spring 15 into engagement with the flange 1' to stop the rotation of the turntable. A stop 27 limits the movement of the detent 16 toward the left. In Fig. 2, the stop mechanism is shown in solid lines in inoperative position, and in dotted lines in operative position.

The arm 17 is pivoted at its forward end to a bell crank lever 28 which is pivoted at 29 to the top of the cabinet 4 (see Fig. 1). The outer end of this arm is flattened as shown at 30 (see Fig. 2), the flattened portion 30 being provided with an elongated slot 31 embracing a pin or projection 32 secured to the lever 13 and projecting from the under side thereof. When it is desired to set the brake mechanism to hold the brake member 13 out of engagement with the flange 1', the lever 28 is rotated in an anti-clockwise direction thereby bringing the projection 32 into engagement with the outer end of the slot 31 and moving the member 13 in an anti-clockwise direction. This movement of the member 13 causes the same

to engage a stop 33 on the detent 16 and 65 to move the latter in a clockwise direction so as to bring the projection 23 into engagement with the notch 24. The forward end of the flattened portion 30 of the member 17 is provided with a downturned projection or flange 34 which is adapted to engage the laterally projecting finger 35 on the detent 16 when the arm 17 is moved forwardly. By rotating the bell crank lever 28 in a clockwise direction, the flange 34 is 70 brought into engagement with the finger 35 to move the projection 23 of the member 16 out of engagement with the notch 24, relative movement between the members 13 and 17 being permitted by the slot 31. It will 75 thus be seen that the brake mechanism may be either set or released by manually operating the lever 28.

The releasing member 12 is preferably formed of two segmental members 36 and 37 pivotally connected as at 38 and engaging in a peripheral recess 39 in the sound conveying arm 5. The members 36 and 37 are connected at the ends remote from the pivotal connection 38 by a spring 40, whereby they are held in frictional engagement with the inner wall of the recess 39. The spring 40 is made of such a strength that the member 12, though movable on the arm 5 by the application of a slight force, is held 80 in place by the said spring sufficiently 85 to release the detent 16. It is evident that only a slight force is necessary to move the detent out of engagement with the member 13. A flange 41 extends upwardly from the edge of section 37 adjacent the member 36 a short distance inwardly of the pivotal connection 38, and a member 42 is rotatably connected with this flange by means of a pivot 43. The forward edge 90 of the member 42 is wedge shaped, as shown at 44, so that when the said member is rotated by the finger hold 45, said wedge shaped portion is forced between the members 36 and 37 to spread the same apart and thereby loosen the member 12 on the sound 95 conveying arm 5, as is clearly shown in Fig. 3. In order to prevent rotation of the member 12 by reason of the frictional engagement between the upper and lower edges of the recess 39 and the said releasing member when it is desired to throw the latter out of operation, the member 37 is provided with a shoulder 46 adapted to be engaged by the arm 47 of a bell crank lever 48 which is pivoted, as shown at 49, to the top of the cabinet. The pivot 49, which is preferably a screw, can be adjusted to regulate the friction on the lever 48 to any desired extent; so that the said lever may be held in adjusted 105 position by frictional engagement with its pivot. In Fig. 2, this lever is shown adjusted 110 to permit the rotation of the releasing 115 member 12.

member 12; but by turning the same in an anti-clockwise direction, the arm 47 may be brought into the path of the shoulder 46 so as to prevent rotation of the releasing member. It is evident that the lever 48 may be used to prevent rotation of the member 12 even when the said member is held in frictional engagement with the arm 5 as shown in Fig. 2; and this lever, may, therefore, be used to render the releasing member inoperative. In order to limit the rotation of the releasing member in an anti-clockwise direction, the member 36 is provided with a shoulder 50 adapted to engage the upwardly extending rear portion of the bracket 7 (see Fig. 1).

The releasing member 12 may be adjusted by hand or by first moving the sound conveying arm away from the axis of the record support to cause the bracket 7 to engage the shoulder 50 and shift the member 12 in a clockwise direction on the arm 5 and by then moving the said arm inwardly to cause the projection 25 on the detent 16 to hold the member 12 stationary until the reproducer is located above the place at which it is desired to stop the reproduction. In this operation, the stop 27 limits the movement of the detent 16. When now it is desired to reproduce the record or section of a record for which the stop mechanism has been adjusted, the reproducer is set at the beginning of the record groove adjacent the periphery of the record and the lever 28 is turned in an anti-clockwise direction to set the brake mechanism in a position for permitting rotation of the record support. When the reproducer comes to the point for which the stop mechanism has been adjusted, the finger 26 of the releasing member moves the detent 16 out of engagement with the member 18 and the spring 15 forces the latter into engagement with the flange 1' to stop the machine.

It is evident that many changes may be made in the construction described above without departing from the spirit of my invention. The brake mechanism may be made to act upon the governor disk or upon any other suitable rotatable part of the phonograph or talking machine; and many other modifications are within the scope of my invention.

What I claim as new and desire to protect by Letters Patent of the United States is as follows:

1. In a device of the character described, the combination with a rotatable member and a traveling member movable relatively to each other, of braking means, a detent therefor, and means connected with said traveling member for automatically releasing said detent to render said braking means operative to stop the rotation of said rota-

table member, said automatic releasing 65 means comprising relatively movable parts and being provided with mechanism for effecting relative movement of said parts for rendering the automatic releasing means inoperative, substantially as described. 70

2. In a device of the character described, the combination with a rotatable member and a traveling member movable relatively to each other, of braking means, a detent therefor, a member for releasing or setting 75 said detent to control the operation of said braking means, means connected with said traveling member for automatically releasing said detent to render said braking means operative to stop the rotation of said rotatable member, said automatic releasing means comprising relatively movable parts 80 and being provided with mechanism for effecting relative movement of said parts for rendering the automatic releasing means inoperative, substantially as described. 85

3. In a device of the character described, the combination with a rotatable member and a traveling member movable relatively to each other, of braking means, a detent 90 therefor, a member for releasing or setting said detent to control the operation of said braking means, and means mounted on said traveling member for automatically releasing said detent to render said braking means 95 operative to stop the rotation of said rotatable member, said releasing means on said traveling member comprising relatively movable parts and being provided with mechanism for effecting relative movement 100 of said parts for loosening the releasing means on said traveling member and to thereby render the same inoperative for releasing said detent, substantially as described. 105

4. In a device of the character described, the combination with a rotatable member and a traveling member movable relatively to each other, of brake mechanism, and means adjustably and directly connected 110 with said traveling member and adapted positively to operate said brake mechanism when said traveling and rotatable members reach a predetermined relative position, the said means being automatically adjustable 115 when in normal operative connection with said traveling member by moving the latter inwardly to a predetermined position relative to the rotatable member, substantially as described. 120

5. In a device of the character described, the combination with a rotatable member and a traveling member movable across the same, of brake mechanism, and means frictionally secured to said traveling member 125 and adapted positively to operate said brake mechanism to stop the rotation of said rotatable member when said traveling member

reaches a predetermined position relatively to the latter, the said brake mechanism being adapted to limit the inward movement of said means to automatically adjust the same on said traveling member when said means is in normal operative connection with said traveling member and upon the inward movement of the latter, substantially as described.

10 6. In a device of the character described, the combination with a rotatable member and a traveling member movable across the same, of brake mechanism, means frictionally secured to said traveling member and 15 adapted to operate said brake mechanism to stop the rotation of said rotatable member when said traveling member reaches a predetermined position relatively to said rotatable member, and means for limiting the 20 movement of said first named means and for moving the same inwardly on said traveling member when the latter is moved away from the said rotatable member, the said brake mechanism being adapted to limit the 25 inward movement of said first named means to automatically adjust the same on said traveling member, substantially as described.

7. In a device of the character described, the combination with a rotatable member 30 and a traveling member movable relatively to each other, of braking means, a detent therefor, manually operable means for releasing or setting said detent to control the operation of said braking means, means connected with said traveling member for automatically releasing said detent to render said braking means operative to stop the rotation of said rotatable member, and means operable to act positively on said last named releasing means to render the same inoperative, substantially as described.

40 8. In a device of the character described, the combination with a rotatable member and a traveling member movable relatively 45 to each other, of braking means, a detent therefor, manually operable means for releasing and setting said detent to control the operation of said braking means, and means operatively connected with said traveling 50 member for automatically releasing said detent to render said braking means operative, said last named releasing means comprising a detent-engaging member pivoted to another part thereof and adjustable about its 55 pivot to render said last named means either operative or inoperative, substantially as described.

9. In a device of the character described, the combination with a rotatable member, 60 of a brake therefor, a detent for said brake and means adapted when moved in one direction to first move the said brake from operative position without any resulting movement of the detent toward operative position and to then effect movement of said de-

tent by means of the brake to lock the latter in inoperative position, and when moved in the other direction, to move said detent to unlock said brake, substantially as described.

70

10. In a device of the character described, the combination with a rotatable member, of a spring-pressed pivotally-mounted brake normally tending to assume a position to hold said rotatable member inoperative, a 75 detent for said brake, and a member adapted when moved in one direction to first move the brake against the action of its spring from operative position without any resulting movement of the detent toward operative 80 position and to then effect movement of said detent by means of the brake to lock the latter in inoperative position, and when moved in the opposite direction, to move said detent to unlock said brake, substantially 85 as described.

80

11. In a device of the character described, the combination with a rotatable member, of a brake therefor, a detent for said brake and a manually operable pivoted controlling 90 member adapted when moved in one direction to first move the brake from operative position without any resulting movement of the detent toward operative position and to then effect movement of said detent by 95 means of the brake to lock the latter in inoperative position, and when moved in the other direction, to move said detent to unlock said brake, substantially as described.

90

12. In a device of the character described, the combination with a rotatable member, of braking means therefor, a detent for said braking means and a controlling member adapted when moved in one direction to first move the braking means to inoperative 100 position and to then cause the braking means to move said detent into locking engagement with said braking means, and when moved in the other direction, to move said detent to unlock said braking means, 105 substantially as described.

100

13. In a device of the character described, the combination with a rotatable member and a traveling member movable relatively to each other, of braking means for said rotatable member, a detent, means separate from said traveling member adapted when moved in one direction to first move said braking means from operative position without any resulting movement of the detent and to then effect movement of said detent by said braking means to lock the latter in inoperative position, and when moved in the other direction, to move said detent to unlock said braking means, and means operatively connected with said traveling member for automatically rendering said braking means operative, substantially as described.

115

14. In a device of the character described, 120

120

125

130

the combination with a rotatable member and another member movable relatively to each other, of braking mechanism, and means adapted to control the operation of said braking mechanism to stop the rotatable member when said members reach a predetermined relative position, said means comprising a device mounted for pivotal movement about a fixed axis only and adjustable about said axis to a position for rendering the braking mechanism operative when said members reach said predetermined position, by relatively moving said members to such predetermined position, substantially as described.

15. In a device of the character described, the combination with a rotatable member and another member movable relatively to each other, of braking mechanism, and means adapted to control the operation of said braking mechanism to stop the rotatable member when said members reach a predetermined relative position, said means comprising a device mounted for pivotal movement about a fixed axis only and adjustable about said axis to a position for rendering the braking mechanism operative when said members reach said predetermined position, by relatively moving said members to such predetermined position when said braking mechanism is inoperative, substantially as described.

16. In a device of the character described, the combination with a rotatable member and another member movable relatively to each other, of braking mechanism, and means adapted to control the operation of said braking mechanism to stop the rotation of said rotatable member when said members reach a predetermined relative position, said means comprising a frictionally mounted device and a device coöperating therewith to render the braking mechanism operative, one of said devices being carried by the second named member, said frictionally mounted device being automatically adjustable by the other device, when in normal operative relation to its mounting, to a position for rendering the braking mechanism operative when said members reach said predetermined position, substantially as described.

17. In a device of the character described, the combination with a rotatable member and a traveling member movable across the rotatable member, of braking mechanism, and means adapted to render said braking mechanism operative to stop the rotatable member when said traveling member reaches a predetermined position, said means comprising a device mounted for pivotal movement about a fixed axis only and adjustable, about said axis, to a position for rendering the braking mechanism operative when said

traveling member reaches said predetermined position, by moving said traveling member inwardly to such predetermined position, substantially as described.

18. In a device of the character described, the combination with a rotatable member and a traveling member movable across the rotatable member, of braking mechanism, and means adapted to render said braking mechanism operative to stop said rotatable member when said traveling member reaches a predetermined position, said means comprising a device mounted for pivotal movement about a fixed axis only and adjustable, about said axis, to a position for rendering the braking mechanism operative when said traveling member reaches said predetermined position, by moving said traveling member to such predetermined position, substantially as described.

19. In a device of the character described, the combination with a rotatable member and a traveling member movable relatively to said rotatable member, of braking mechanism and means adapted to release said braking mechanism for stopping the rotatable member when said members reach a predetermined relative position, said releasing means comprising a device mounted for pivotal movement about a fixed axis only and adjustable about said axis to a position for releasing the braking mechanism when said members reach said predetermined position by relatively moving said members to said predetermined position.

20. In a device of the character described, the combination with a rotatable member, of a brake therefor, a detent for said brake, and means adapted when moved in one direction to first move said brake from operative position without any resulting movement of the detent toward operative position, and to then effect the movement of said detent to operative position by means of the brake, substantially as described.

21. In a device of the character described, the combination with a rotatable member, of a brake therefor, and a detent for said brake, said brake being movable from operative position a predetermined amount without any resulting movement of said detent, the brake in its further movement from operative position positively moving said detent to operative position, substantially as described.

22. In a device of the character described, the combination with a rotatable member and another member movable relatively thereto, of braking mechanism, and means adapted to control the operation of said braking mechanism to stop the rotatable member when said members reach a predetermined relative position, said means comprising a frictionally mounted device and a device coöperating therewith to render the braking mechanism operative, one of said

- devices being carried by the member movable relatively to the rotatable member, said frictionally mounted device being adjustable by the other device to a position for rendering the braking mechanism operative when said members reach said predetermined position by relatively moving said members to such predetermined position, substantially as described.
- 10 23. A stop mechanism comprising a brake, a detent therefor, and means for causing the brake to exert a force tending to move said detent to operative position when the brake is moved to inoperative position, substantially as described.
- 15 24. A stop mechanism comprising a brake and a detent therefor, said detent being movable to operative position by said brake when the latter is moved to inoperative position, substantially as described.
- 20 25. In a machine for reproducing sound, the combination with a rotatable table, of a swinging arm movable over the top of the table, a brake mechanism arranged to engage the table, and a brake releasing device arranged on the swinging arm for coöperation with the brake, said brake releasing device embodying a slidable member adjustable laterally of the swinging arm and co-operating with the brake.
- 25 26. In a machine for reproducing sound, the combination with a rotatable table, of a swinging arm movable over the top of the table, a brake mechanism arranged to engage the table, and a brake releasing device arranged on the swinging arm for coöperation with the brake, said brake releasing device embodying a guide, and a slidable member arranged on the guide and coöperating with the brake.
- 30 27. In a machine for reproducing sound, the combination with a rotatable table, of a swinging arm movable over the top of the table, a brake mechanism arranged to engage the table, and a brake releasing device arranged on the swinging arm for coöperation with the brake, said brake releasing device embodying a curved guide, and a curved slidable member arranged on the guide and coöperating with the brake.
- 35 28. A talking machine comprising a braking element and a latching element having complementary engaging members whereby the braking element is restrained in its off position, a brake-setting spring attached to said braking element, means on the braking element for positively alining said engaging members by the retracting movement of the braking element, and a trip-member connected with the latching element and adapted, when engaged at the end of the selection, to move said latching element so as to release the braking element and permit the latter's spring to set the brake.
- 40 29. In a device of the character described, a rotatable member, a brake for said member biased to operative position and movable to inoperative position, and means for holding said brake in inoperative position, said means being movable to operative position by movement of the brake from operative position, substantially as described.
- 45 30. In a device of the character described, a rotatable record support, a sound conveyer mounted to swing over said support, a brake for said support, means for holding said brake in inoperative position, said means being movable to operative position by movement of the brake from operative position, and means controlled by said sound conveyer in the movement thereof over said support to effect the release of said holding means, substantially as described.
- 50 31. In a device of the character described, a rotatable record support, a lever carrying a brake for said support, and a detent arranged to be moved by said lever to a position for holding the latter in a position where the brake is inoperative, substantially as described.
- 55 32. In a device of the character described, the combination with a rotatable member and another member movable relatively thereto, of braking mechanism comprising a brake for said rotatable member and a detent movable by the brake to a position for holding the latter in inoperative position, and means adapted to trip said detent and release the brake when said members reach a predetermined relative position, said means comprising a frictionally mounted device carried by the member movable relatively to the rotatable member, substantially as described.
- 60 33. In a device of the character described, the combination with a rotatable member, and another member movable relatively thereto, of braking mechanism, and means adapted to control the operation of said braking mechanism to stop the rotatable member, said means comprising an adjustably mounted device and a device coöperating therewith to render the braking mechanism operative, one of said devices being carried by the member movable relatively to the rotatable member, said adjustably mounted device when in a position in engagement with the other device after said members have been initially set to a predetermined relative position, being adjusted so as to render the braking mechanism operative when said members again reach said predetermined relative position, substantially as described.
- 65 34. In a device of the character described, the combination with a rotatable member and another member movable relatively thereto, of a brake for said rotatable member, a detent movable by the brake to a position

tion for holding the latter in inoperative position, and a device for tripping said detent adjustably mounted on the member movable relatively to the rotatable member, said device when in a position in engagement with said detent after said members have been initially set to a predetermined relative position, being adjusted so as to trip said detent and release the brake when

said members again reach said predetermined relative position, substantially as described.

This specification signed and witnessed this 1st day of May, 1911.

CHARLES SCHIFFL.
